ORCHARD HEATER

Howard J. Lambert and Ellis R. Merifield, Los Angeles, Calif., assignors to said Howard J. Lambert

Application April 21, 1937, Serial No. 138,146

3 Claims. (Cl. 158—91)

Our invention relates to orchard heaters and has for its main object to provide means for burning the smoke, or causing a more perfect combustion, whereby to avoid the escape of such smoke and the products of combustion into the atmosphere with the attendant evils.

Many attempts have been made to secure this more perfect combustion, and we have by many long experiments and reconstructions and changes finally succeeded in producing an orchard heater with means for consuming all of the smoke and products of combustion, and have provided such means so that it can be placed over the usual fuel bowl now used in many heaters, or it can be used in connection with any source of smoke to prevent its escape into the atmosphere.

Among the salient objects of our invention are: To provide a construction and arrangement of parts to receive the smoke or gases and products of combustion from the source of production and by means of retardation, whirling action and mixing of atmospheric air therewith, to cause a complete combustion of such smoke or products of combustion; to provide in connection therewith a secondary combustion or expansion chamber to which and through which said mixture of air, gases and products of combustion passes for further combustion; to provide in connection with a device of the character referred to an overhanging canopy designed to reflect or deflect the heat downwardly around the structure, whereby to maintain a higher temperature in and around the structure; and, in general, to provide a more efficient means for consuming the smoke and products of combustion coming from an orchard heater or other device producing the same, whereby to eliminate the objectionable features now common in all orchard heaters, smudge pots and the like.

In order to fully explain our invention, we have illustrated one practical embodiment thereof, as embodied in an orchard heater, which we will describe.

In the drawing, Figure 1 is a vertical sectional view through an orchard heater with our invention applied thereto;

Figure 2 is a cross sectional view taken on the line 2—2 of Fig. 1; and

Figure 3 is a fragmentary view of the side of a member having air-inlet openings therethrough.

Referring now in detail to the drawing, we will describe the structure here shown as one embodiment of our invention. It will be understood, of

course, that the drawing is illustrative and that the proportions and dimensions are only illustrative also and that changes in measurements, materials and general arrangements can be varied within the scope of our invention. In some cases the parts or structures are exaggerated for clearness.

In the drawing 5 designates a fuel bowl or reservoir with a filling opening at 6, with cap provided with air inlet openings therethrough, which can be regulated as to the size of said inlet openings, in the usual and well known manner. This cap is designated 7.

Mounted on the neck 5' of said bowl, is a shield or member 8, shown of conical form and provided around its bottom 9, outside of said neck 5', with openings 9' and in its side is provided with series of air inlet openings, as 10, said openings being formed by striking inwardly a portion of the material, as at 10', whereby the material is sheared and an inwardly projecting portion 10' is the result.

Said openings are formed at different angles, as will be better understood from Fig. 3. The lower row of openings stand at approximately forty-five degree angle relative to the vertical, as at 11, 11. The next upper row stands at approximately thirty degrees, as at 12, 12. The next row stands at approximately fifteen degrees, as at 13, 13, and the upper row stands practically vertically, as at 14, 14. This arrangement serves to cause the inflowing air to whirl within the shield 8.

Mounted within said shield 8, is an inverted dome-like member 15, of material sufficiently heavy to stand the heat, such as cast iron, or other suitable material, said dome member being supported on the bottom of the shield 8 by three legs, 16, 16. Said dome terminates in a discharge, stem-like portion 15'.

Within said dome-like member 15, stands an air inlet pipe 17 having a flaring upper end 17' and surrounded by a sleeve member 18, to form an air space 19 around said pipe 17. Said pipe 17, at its lower end connects with a pipe 20, which is extended laterally and down through the bottom 9 of said shield 8, as shown, and also provided with a flaring inlet mouth at 21 to direct air upwardly into said dome 15.

Mounted on the upper end of said shield 8, is an expansion drum 22, which is shown of larger diameter around its middle portion than at its opposite ends, substantially as illustrated, though its dimensions can be varied somewhat in actual

use, and as may be required, according to the general size of the completed structure.

5 Mounted over the upper end of said drum 22 is a canopy or hood 23, which extends outwardly and downwardly sufficiently to reflect or deflect the heat downwardly around the fuel bowl and the surrounding ground, whereby to increase the area around the heater in which the temperature is considerably raised by the reflected heat.

10 A stack, of any suitable height, designated 24 is mounted on the drum 22, above the canopy 23.

The use and operation of our invention may be briefly described as follows:

15 The oil in the reservoir 5 is ignited through the opening at 7, in the usual manner, with the result that a generation of heated gas rises therefrom. The dome 15 has the restricted outlet or flue 15' which retards the upflow, and the outer member 8, in connection with said dome 15 and flue 15' creates a Venturi tube structure, around the top of said dome 15 and said flue 15' for the air passing upwardly through the openings 9' in the bottom of said member 8, and the gases which may escape under the edge of said dome member 15, and the air inlet openings 10, 10, which cause a whirling movement of the upwardly flowing air and gas, and these all mingle in the expansion drum 22. The heat developed is reflected or is directed downwardly around the fuel reservoir 5 and the member 8, and this all tends to maintain the oil and gases in a heated condition. The superior heat within the chamber 15 brings the gases up to a very high temperature, and as air is being admitted through air tube 20, also preheated, an explosive mixture of air and gas is formed and ignited. The explosion inside of chamber 15 is not of a turbulent type, but is one of force, forcing some of the gases out at the bottom of said dome member 15, so as to pass over the air ports 9' and then upwardly in mixing engagement with the air flowing inwardly through the openings 10. The rotation movement of the air through the openings 10 slows up the vertical rise somewhat and a better combustion is thus promoted. The explosion of the gases in the dome member 15 also causes a forced flame out through the flue 15', which further ignites any of the preheated gases that may have passed through the lower

50 chambers of combustion.

By much experimenting this general construction and arrangement has been found to be most practical and its operation has been with great heat and without any smoke from the stack, and 55 in its operation there is produced a puffing or vibration something like that of a locomotive, uniform and rapid.

Thus we have provided an orchard heater in which, in addition to the fuel bowl in which the 60 fuel is ignited, there is a primary combustion

chamber, that is, within the dome-like member and the shield, and a secondary combustion chamber, within the member 22, all so arranged and related to each other that a more perfect combustion and burning of the fuel and products of combustion is accomplished, and while we have shown and described in detail one practical embodiment of our invention, we are aware that changes in details can be made without departing from the spirit of the invention, and we do not 10 limit our invention to the showing made, except as we may be limited by the hereto appended claims.

We claim:

1. In an oil burning heater, the combination 15 with a bowl for fuel oil having an opening in its top, an inverted bowl-like member over said opening to receive products of combustion and gases from said opening, said member having a stem-like extension extending upwardly therefrom, 20 means for admitting atmospheric air to the inside of said bowl-like member in alignment with said stem-like extension outlet therefrom, a shield around said bowl-like member having openings therein for the admission of air to the space 25 around the outside of said bowl-like member within said shield, and a stack structure above said shield and said bowl-like member.

2. Means for burning the smoke and products of combustion which includes a conical shaped 30 outer shield having air inlet openings through its side and open at its bottom to receive said products of combustion from a source, a dome-like member of less diameter in said shield and opening over the inlet to said shield, said dome-like member having a stem-like extension forming a restricted outlet flue therefrom, an air inlet tube extending from outside of said shield to the inside of said dome-like member and opening in alignment with the stem-like extension, 40 and a stack structure over said shield with a part forming a second combustion chamber above said shield and said dome-like member.

3. In combination, a conical shield member open at its bottom to receive products of combustion and gases from a source and having tangentially positioned air inlet openings through its side, an inner conical member with its bottom open above the inlet to said shield and terminating in a reduced stem-like portion forming a restricted outlet therefrom, an air inlet tube extending from the outside of said shield to the inside of said dome-like member with its outlet disposed in alignment with the outlet from said dome-like member, a member above said shield 55 forming a second combustion chamber, a stack and a canopy around said structure for deflecting heat downwardly around said structure.
